(57) **CLAIM**

The ornamental design for an intake manifold, as shown and described.

DESCRIPTION

FIG. 1 is a top, front perspective view of the intake manifold;

FIG. 2 is a front elevation view of the intake manifold;

FIG. 3 is a back elevation view of the intake manifold;

FIG. 4 is a left side elevation view of the intake manifold;

FIG. 5 is a right side elevation view of the intake manifold;

FIG. 6 is a top plan view of the intake manifold; and,

FIG. 7 is a bottom plan view of the intake manifold.

The broken lines shown in the drawings are for the purpose of illustrating portions of the article that form no part of the claimed design.
